UNITED STATES PATENT OFFICE.

SIMON FABIAN KJELL, OF MALDEN, MASSACHUSETTS.

LITHOGRAPHER'S PRESS.

Application filed November 28, 1922. Serial No. 603,843.

To all whom it may concern:

Be it known that I, SIMON F. KJELL, a citizen of the United States of America, and a resident of Malden, in the county of 5 Middlesex and State of Massachusetts, have invented certain new and useful Improvements in Lithographers' Presses, of which the following is a specification.

This invention relates to presses and particularly to presses for use by lithographers, and the object of the invention is the production of an inexpensive device of this character which may be used in the home to print a limited number of lithographs or 15 artists' proofs.

Another object of the invention is the production of a device of this character which may be utilized as a table by an artist while producing his work upon the stone from 20 which the lithographs are to be subsequently printed.

The invention consists of a table having superimposed thereon a framework provided with a sheet backer and a movable member 25 adapted to be moved over the surface of the backer to produce an impression from the stone upon the sheet of material superimposed thereon.

The invention further consists of certain 30 novel features of construction and arrangement of parts which will be understood readily by reference to the description of the drawings and to the claims to be herein-after given.

For the purposes of illustrating the invention, one preferred form thereof is shown in the drawings, this form having been found to give satisfactory and reliable results, although it is to be understood that the various instrumentalities of which the invention consists can be variously arranged and organized, and that the invention is not limited to the precise arrangement and organization of the instrumentalities as herein 45 shown and described, except as required by the scope of the appended claims.

Of the drawings:

Figure 1 represents a plan of a machine embodying the principles of the present invention.

Figure 2 represents a vertical section of same on line 2, 2 on Fig. 1.

Figure 3 represents an end elevation of the same.

Figure 4 represents a vertical section on line 4, 4 on Fig. 2.

Figure 5 represents a vertical section on line 5, 5 on Fig. 2, and

Figure 6 represents a sectional detail on line 6, 6 on Fig. 2.

Similar characters indicate like parts throughout the several figures of the drawings.

In the drawings, 10 is a bed supported upon the legs 11. This bed 10 has a slot 12 in one end thereof in which is positioned the head 13 of a threaded member 14 extending upwardly from the bed 10 and having threaded thereto a shouldered nut 15.

Between the shoulders of the nut 15 is disposed a cross bar 16 of a frame 17 adapted to be raised and lowered relatively to the upper face of the bed 10 when the nut 15 is rotated about the axis of the perpendicular threaded member 14.

At the rear of the bed 10 is secured an upwardly extending plate 18 against which the rear side of the frame 17 contacts, this plate preventing the rotation of the frame 17 about the axis of the member 14 when the frame 17 is being raised or lowered.

The bed 10 is adapted to support a lithographic stone 19, and above this stone 19 is a framework 20 hinged at 21 to the left or inner end of the frame 17. This framework 20 may be moved about the axis of the pins of the hinges 21 to secure access to the stone 19. When the framework 20 is moved from contact with the stone 19, it is adapted to rest upon the support 22 secured to one end of the frame 17.

Secured to the under part of the framework 20 is a backer plate 23 preferably formed of flexible metal and normally free from contact with the stone 19 or a sheet of paper superimposed thereon.

One end of the backer 23 is clamped at 24 and the other end has a spring 25 secured thereto, the opposite end of which is secured to the bracket 26, depending from the framework 20.

Between the side bars of the framework 20 is a carriage 27 adapted to be moved lengthwise of the framework 20 by means of cords or wires 28 which at one end are secured to the carriage, while the opposite ends thereof are secured to the rotatable drum 29 mounted upon a shaft 30 revolu-

bly mounted in bearings in the frame 17. This shaft 30 is adapted to be rotated by means of a crank 31, and may also be moved endwise.

8 Pinned or otherwise secured to the shaft 30 is a clutch member 32 adapted to engage with a coacting clutch member 33 on the revoluble drum 29, said drum normally being retained in position indicated in Fig. 1 10 by means of the spring 34 as shown in said Fig. 1. When in this position the clutch members 32 and 33 are disengaged.

When it is desired to move the carriage 27 to the right of Figs. 1 and 2, the operator forces the shaft 30 to the rear until the clutch members 32 and 33 engage, then by rotating the crank 31, the carriage is moved lengthwise of the framework 20. As soon as the operator releases the crank 31, the spring 34 will act to return the shaft 30 to its normal position as shown in Fig. 1 of the drawings.

The carriage 27 has a slot therein in which is disposed a wiper member 35, the lower end of which is tapered with the edge thereof contacting with the upper face of the flexible plate 23. Upward movement of the wiper member 35 is prevented by means of the top plate 36 and shoulders on said wiper 35 bearing against the under face of the carriage 27, and said wiper member is secured in position in its slot by means of the set screw 37.

In the free end of the framework 20 is mounted a threaded member 38, the lower end of which has a hook 39 formed integral therewith.

Rotatably mounted in the free end of the framework 20 and prevented from end 40 movement, is an adjusting nut 40 threaded to the member 38. By rotating this nut 40, the position of the hook 39 may be adjusted relatively to the framework 20.

To the under face of the left hand end 45 of the bed 10 is a slotted plate 41, in a hole through which is disposed the upper end of a rod 42, the lower end of said rod 42 being positioned in a slot in the plate 43 secured to a cross bar 44 between the legs 11, 11 50 at the left of the machine.

The upper end of the rod 42 has secured thereto a slotted member 45 through the slot of which the projection 46 on the hook 39 is adapted to extend. To the cross bar 44 is 55 pivotally mounted at 47 a lever 48, having an extension 49 on the other side of said pivot carrying a counter weight 50. This weight 50 is sufficient to normally retain the lever 48 in the position indicated in Fig. 3 of the drawings, and to return it to its normal position when the lever has been moved in the direction of the arrow α on Fig. 3 of the drawings.

The lever 48 has a pin 51 mounted therein eccentrically to the pivot 47, this pin 51 ex-

tending through a slot 52 in the lower end of the rod 42. Between the left end of the bed 10 and the rod 42 is one end of a lever 53 pivoted at 54 to said bed 10 and normally held free from contact with the rod 42 by means of a spring 55 positioned in a hole in the end of the bed 10.

When it is desired to print from the lithographic stone 19, the operator presses against the end 56 of the lever 53, forcing the opposite end thereof against the rod 42 and moving it laterally in the slot of the plate 43 sufficiently to disengage the slotted member 45 from the projection 46 on the hook 39. When the hook 39 is thus disconnected from the member 45, the framework 20 may be moved about the hinges 21 onto the support 22.

A sheet of paper is then placed upon the lithographic stone 19 and the framework 20 is then returned to its normal position as indicated in Figs. 1 and 2 of the drawings.

In the downward movement of the framework 20, the curved portion of the projection 46 will come into contact with the curved upper end 57 of the member 45, forcing said member outwardly a sufficient distance to permit the projection 46 to again enter the slot in the member 45.

When the projection 46 has come to a point opposite to the slot in the member 45, the spring 58 connected at one end to a pin 59 in the bed 10 and with the opposite end thereof connected to the plate 41, through which the rod 42 extends, will act to move said rod 42 toward the end of the bed 10 and permit the projection 46 to enter the slot in the member 45.

The operator then grasps the lever 48 and moves it in the direction of the arrow α on Fig. 3 of the drawings, thereby moving the free end of the framework 20 downwardly a distance sufficient to give the proper impression upon the backer 23 above the sheet of material to be printed upon.

It is obvious that this framework 20 when in position to print must be parallel with the upper face of the stone 19, and the revoluble nuts 15 and 40 may be adjusted so that, regardless of the thickness of the stone and the impression desired, the frame 17 and framework 20 may always be adjusted in the proper position parallel to the stone 19.

When these adjustments have been made by means of the nuts 15 and 40, the operator grasps the handle of the crank 31 and rotates the same clockwise, drawing the carriage 27 toward the right of the machine, the wiper member carried thereby forcing a portion of the backer 23 into contact with the sheet of paper being printed upon.

As the wiper member 35 is drawn across the backer 23, only that portion of the

backer opposite the wiper 35 will be forced into contact with the sheet of paper or other material, the remaining portions of the backer being free from contact with said sheet.

When the wiper member 35 has reached the right hand end of the framework 20, said framework 20 will again be disengaged from the slotted member 45 and moved about its hinges onto the support 22, permitting the printed sheet to be removed from the stone. A new sheet is then superimposed upon the stone, the framework 20 is returned to its normal position and locked, and then the carriage is returned to its normal position at the left of the framework 20, preparatory to another operation.

At one end of the machine there is preferably secured a receptacle 58 in which the sheets to be printed upon may be retained.

When the artist desires to work upon the stone 19 supported by the bed 10, the head 13 may be removed from the slot 12, thereby removing the frame 17 and the framework 20, giving the artist ample room to work upon the stone. When this work had been finished, the frame 17 and framework 20 may be returned to their normal position as indicated in the drawings and the printing resumed.

It is believed that the operation and many advantages of the invention will be understood readily without further description.

Having thus described my invention, I claim:

1. The combination of a bed adapted to support a lithograph stone; a frame positioned above said bed and adjustable relatively thereto; a framework hinged to said member and normally positioned above said stone; a backer plate on said framework normally free from contact with said stone, one end of said backer plate having a yielding connection; means reciprocable lengthwise of said framework and coacting with said backer plate to create an impression from said stone; and means for adjusting the position of the free end of said framework relatively to said bed.

2. The combination of a bed adapted to support a lithograph stone; a member removably positioned upon said bed and extending upwardly therefrom; a frame adjustable vertically upon said member and normally positioned above said stone; a framework hinged to said frame; a backer plate on said framework above and normally free from contact with said stone; means reciprocable lengthwise of said framework and coacting with said backer plate to create an impression upon a sheet disposed upon said stone; and means for adjusting the position of said frame relatively to said bed.

3. The combination of a bed adapted to

support a lithograph stone; a frame positioned above said bed and adjustable relatively thereto; a framework hinged to said frame and normally positioned above said stone; a backer plate on said framework above and normally free from contact with said stone; means reciprocable lengthwise of said framework and coacting with said backer plate to create an impression from said stone; and means for adjusting the position of the free end of said framework relatively to said bed.

4. The combination of a bed adapted to support a lithograph stone; a frame positioned above said bed and adjustable relatively thereto; a framework hinged to said frame and normally positioned above said stone; a backer plate on said framework above and normally free from contact with said stone; means reciprocable lengthwise of said framework and coacting with said backer plate to create an impression from said stone; and means for locking the outer end of said framework; and means for adjusting the position of the free end of said framework relatively to said bed.

5. The combination of a bed adapted to support a lithograph stone; a threaded post extending upwardly from said bed; a revolvable nut thereon; a frame supported by said nut; a framework hinged to said member; and impression creating means movable on said framework over the face of said stone.

6. The combination of a bed adapted to support a lithograph stone; a frame supported above said bed and adjustable relatively thereto; a framework hinged to said frame; a hook adjustably mounted in the free end of said framework; locking means on the end of said bed engaging said hook; and impression creating means movable on said framework over the face of said stone.

7. The combination of a bed adapted to support a lithograph stone; a frame supported above said bed; a framework hinged to said frame; a hook in the free end of said framework; an impression bar movable on said framework over the face of said stone; and means on the end of said bed for creating a downward pull on said hook.

8. The combination of a bed adapted to support a lithograph stone; a frame positioned above said bed; a framework hinged to said frame and normally positioned above said stone and parallel thereto; a reciprocating carriage on said framework; an impression bar carried by said carriage and adapted to be moved over the face of said stone; and manually actuated mechanism on the end of said bed for moving said framework toward said bed.

9. The combination of a bed adapted to support a lithograph stone; a frame positioned above said bed; a framework hinged to said frame and normally positioned above

said stone and parallel thereto; a backer plate suspended from said framework and yieldingly connected thereto, said backer plate being normally free from contact with said stone; and means reciprocable lengthwise of said framework and coacting with said backer plate to create an impression from said stone.

10. The combination of a bed adapted to support a lithograph stone; a framework normally positioned above said stone; a backer plate suspended from said framework and yieldingly connected thereto, said backer plate being normally free from contact with said stone; and means movable on said framework for forcing a portion of said backer plate toward said stone and thereby creating an impression from said stone.

11. The combination of a bed adapted to support a lithograph stone; a framework normally positioned above said stone; a backer plate suspended from said framework and yieldingly connected thereto, said backer plate being normally free from contact with the stone; means movable lengthwise of the

framework for successively forcing a portion of the backer plate toward said stone and creating an impression therefrom; and means for independently adjusting the opposite ends of said framework relatively to the face of said stone. 30

12. The combination of a bed adapted to support a lithograph stone; a framework positioned above and parallel to said bed; a reciprocating carriage on said frame; crank mechanism for moving said carriage lengthwise of said frame; a flexible backer suspended from said framework and yieldingly connected thereto; and an impression bar carried by said carriage and adapted to be moved over the backer in a path parallel with the face of said stone. 35 40

Signed by me at 746 Old South Bldg., Boston, Mass., this 25th day of November, 1922.
